UNITED STATES PATENT OFFICE.

STERLING H. CAMPBELL, OF ST. LOUIS, MISSOURI.

BRAKE-ROD JAW.

1,391,716.

Specification of Letters Patent. Patented Sept. 27, 1921.

Original application filed October 15, 1919, Serial No. 330,944. Divided and this application filed July 9, 1920. Serial No. 394,929.

U.S.1. J. CAMPBELL IN BREVITY

To all whom it may concern:

Be it known that I, STERLING H. CAMPBELL, a citizen of the United States of America, residing at the city of St. Louis, State 5 of Missouri, United States of America, have invented certain new and useful Brake-Rod Jaws, of which the following is such a full, clear, and exact description as will enable any one skilled in the art to which it apper- 10 tains to make and use the same, reference being had to the accompanying drawings, forming part of this specification.

My invention relates to a brake rod jaw and more particularly to a forged metal 15 brake rod jaw of the nonwelding type.

One object of my invention is the production of a suitable forged metal blank from which the brake rod jaw may be formed by boring or punching pin eyes and rod eyes in 20 the blank. Another object of my invention is to so form a blank that one size and shape of blank may be utilized to produce brake rod jaws for varying sizes of brake rods.

In the accompanying drawings which 25 illustrate two forms of brake rod jaws made in accordance with my invention, Figure 1 is a side view of the blank for producing my preferred form of brake rod jaw, Fig. 2 is an edge view of the same, Fig. 3 is a longitudinal section of the completed jaw, the 30 brake rod being shown in position. Fig. 4 is an end view of the part shown in Fig. 3. Fig. 5 is a plan view of a blank for producing a modified form of jaw. Fig. 6 is a 35 section taken on the line 6-6 of Fig. 5, Fig. 7 is a side view of the completed jaw formed from the blanks shown in Figs. 5 and 6, the 40 brake rod being shown in position, and Fig. 8 is an edge view of the jaw shown in Fig. 7, the brake rod being omitted.

Referring first to Figs. 1 to 4 inclusive, 10 indicates a rod base which has formed integral with it a pair of arms 11 each terminating in an enlarged end 12 preferably circular 45 in shape. Situated between the arms 11 and formed integral therewith is a rod seat 13. All the parts of the blank taper from a central dividing line 14, so that the forming die may have the necessary draw, and conse- 50 quently the central parts of the enlarged ends 12 project beyond the sides of the arms 11 as indicated at 15 in Fig. 2. This surplus metal, however, is removed when the pin eyes 16 are formed in the ends 11 by punch- 55 ing or boring, as indicated by the dotted lines in Fig. 4. 17 are rod eyes which are

formed in the rod base 10 and adapted to receive the two portions of the brake rod 18 resulting from the formation of the return bend 19 which seats against the rod seat 13. 60 The rod base 10 is made of such size and shape that various sized rod eyes 17 may be formed therein to coöperate with the same rod seat 13 so that one form and size of blank may be used to produce rod jaws for 65 rods of varying sizes. The part 20 of the rod base lying between the two rod eyes 17 forms a rod bending support at one side of recesses 21 into which a portion of the rod 18 is adapted to be bent, the rod seat 13 forming a rod bending support at the other side of 70 said recesses. By striking the rod 18 at the point 22 with a suitable tool, the rod is bent in to the recess 21 thus effectively preventing its retrograde movement relative to the 75 jaw.

In Figs. 5 to 8, I have shown a modified form of brake rod jaw which is formed from a blank forged out of flat sheet metal as shown in Fig. 5. In this form of jaw the 80 pin eyes 16 and rod eyes 17 are formed during the operation of forging the blank and at the same time openings 23 are formed in the blank to receive a bolt or rivet to form a rod seat 24 in lieu of the integral rod seat 85 13 of the form of jaw hereinbefore described. In this form of jaw the open space 25 between the part 20 of the rod base and the rod seat 24 forms the recess into which a portion of the rod is adapted to be bent by 90 striking it at the point 22, to prevent its retrograde movement relative to the jaw.

This application is a division of application Serial No. 330,944, filed Oct. 15, 1919.

Having fully described my invention, 95 what I claim as new and desire to secure by Letters Patent of the United States is:

1. A forged metal blank for forming brake rod jaws, comprising a pair of arms terminating in enlarged ends for the pin 100 eyes, said ends having their central parts extending beyond the sides of the arms, said extending parts being adapted to be removed by the perforation of the ends to produce the pin eyes.

2. A forged metal blank for forming brake rod jaws, comprising a rod base, and a pair of arms integral with said base, all parts of said blank tapering from a central parting line.

3. A forged metal blank for forming brake rod jaws, comprising a rod base and a

105

110

pair of integral arms terminating in enlarged ends for the pin eyes, all parts of said blank tapering from a central parting line, the surplus metal of the enlarged ends being adapted to be removed by the perforation of said ends to produce the pin eyes.

4. A forged metal blank for forming brake rod jaws, comprising a pair of arms, a rod seat between said arms adapted to re-

ceive rods of varying diameter, and a rod base formed integral with said arms and adapted to have rod eyes of varying diameters formed therein, each to completely surround one side only of a rod loop.

In testimony whereof, I have hereunto set my hand and affixed my seal.

STERLING H. CAMPBELL. [I. S.]
